UNITED STATES PATENT OFFICE

171,248

SET OF CHESSMEN OR SIMILAR ARTICLE

Raymond P. Cimillo, Bronx, N. Y.

Application March 13, 1953, Serial No. 24,024

Term of patent 7 years

(Cl. D34—5)

To all whom it may concern:

Be it known that Raymond P. Cimillo, a citizen of the United States of America, residing at Bronx, New York, in the county of Bronx and State of New York, have invented a new, original, and ornamental Design for a Set of Chessmen or Similar Article, of which the following is a specification, reference being had to the accompanying drawing, forming part thereof.

Figs. 1 to 6, inclusive, are perspective views of the chessmen in a set of chessmen or similar article, showing my new design.

I claim;

The ornamental design for a set of chessmen or similar article, as shown.

RAYMOND P. CIMILLO.
